UNITED STATES PATENT OFFICE

CHARLES WILLS ABBOTT, OF ROME, NEW YORK, ASSIGNOR, BY MESNE ASSIGNMENTS, TO GENERAL CABLE CORPORATION, OF NEW YORK, N. Y., A CORPORATION OF NEW JERSEY

ELECTRICAL CONDUCTOR

Application filed September 18, 1924. Serial No. 738,340.

The present invention relates to improvements in insulated electrical conductors or cables which are particularly adapted for use where exposed to the weather and other deteriorating influences.

The object of the invention is to provide an electrical conductor or cable which will be satisfactorily insulated and suitably constructed to withstand all the effects of overloading the 10 electrical circuits, which cannot be easily damaged by fire, water, alkali, salts, abrasion, oil, or impact and which in other respects will be eminently satisfactory when used for any appropriate purpose. Further objects of the 15 invention will be in part obvious and in part specifically pointed out in the following description of a preferred and illustrative embodiment thereof.

It is of prime importance that the wires 20 which are to be used for certain purposes where exposed shall be well insulated electrically. It is equally essential that the insulated conductor or cable formed by the encasing of wires in rubber compounds or other 25 electrically insulating material be protected against mechanical injury which would tend to break down the insulation and permit short circuits or grounds to occur. It is desirable that such mechanical protection should also 30 increase the electrical protection afforded by the usual rubber compound and should be of such a character that it will not be injuriously affected by the tensile and torsional strains to which the conductors are subjected by bending and by accidental blows or pressure. The 35 conditions under which wires or cables are installed also necessitate the use of a protective covering which will remain substantially unaffected by atmospheric changes and will 40 not deteriorate when subjected to moisture or water over a relatively long period of time.

For example, such conductors may be installed in the underbody wiring of street cars where the material is exposed to a great 45 deal of moisture, to wheel wash, heat, cold, oil, and to salts and alkalis, such as are used to keep switch frogs clear of ice during winter weather. It is of great importance that the protective covering of the insulated wires 50 be highly resistant to fire whether the same

originates inside the conductor, as by an over-load, or outside the conductor, in fact the entire mode of constructing the conductor or cable is directed to minimizing the destructive effects of fire as well as of water and various corrosive materials.

The conductors or cables constructed and protected in accordance with the present invention provide a homogeneous compact structure of materials all of which have insulating 60 properties. They are of a construction in which there are no appreciable air spaces, which is well protected against abrasion, moisture and alkalis which is relatively flexible and which will, because of the several 65 compounds with which it is impregnated, resist the action of any fire that may originate inside or outside the conductors and which is a relatively poor conductor of heat.

It is contemplated that the present invention may find a principal application to electric conductors and cables used in the underbody wiring of street cars, and electric locomotives, on ships, as underground conductors and the like and I have selected for purposes 70 of illustration a multiple conductor or cable particularly adapted for such use. The nature and objects of the invention will be better understood from the following description 75 of such a preferred embodiment.

In the accompanying drawing forming a part hereof,

Figure 1 is a view of a section of cable showing parts progressively removed to show the structure of the cable.

Figure 2 is a cross-sectional view of the same.

The structure shown in the drawing for the purpose of illustrating the invention comprises a plurality of metallic conductors 5 80 which are covered with an insulating compound 6. The metallic conductors 5 are here shown as comprising a number of wires twisted together to form each conductor. The insulating compound may be applied to the wires and cured in any suitable manner and preferably has a high percentage of rubber so that the conductors will be adequately protected electrically.

The conductors covered with the insulating

compound are each encased in a helically wound strip of protective material 8 which preferably takes the form of a strip of insulating fibrous material such as paper which 5 may be of laminated construction. The particular form of tape shown consists of a strip of relatively thin kraft paper repeatedly folded upon itself until a tape of the required thickness has been built up. This 10 folding may be accomplished by suitable dies or rollers of such a character that a compact tape structure is secured. In the present instance the strip of paper is folded six times. Inasmuch as this particular form of tape by 15 itself forms no part of the present invention it will not be further described herein.

The tape so formed or any other suitable strip of protective material may be carried upon suitable reels or spools in a suitable 20 winding machine which will carry the reels or spools around the insulated wire as it is drawn along the axis of rotation thereof so that the tape will be tightly wound onto the wire in the form of a closed helix. In this 25 manner a very substantial mechanical as well as electrical protection is afforded for the rubber compound.

Preferably a cotton braid 10 is applied over the paper wrapping 8 which conveniently 30 may be done by leading the wrapped conductor to a braiding machine. The braid is preferably rather open but nevertheless tightly braided upon the paper to hold it securely in place.

35 Inasmuch as the paper tape and cotton braid are naturally inflammable they are treated or impregnated as indicated at 11 to render them fire resisting and at the same time reasonably moisture proof, a treatment which 40 is preferably carried out after the two materials have been placed upon the conductor. The compound may also act as a binder to hold the braid and tape in place. I prefer to use a fire resisting and moisture proofing compound 45 containing as the principal ingredients zinc oxide and silicate of soda, with a small percentage of suitable ingredients to hold the same in suspension.

50 In such a compound the fire resisting properties are probably greater than the moisture proofing properties. This compound may be applied in any suitable manner as by leading the braided conductor to an open tank containing the compound in suitable condition 55 as to viscosity and temperature. The compound will penetrate through the open braid 10 and impregnate to a substantial extent the paper wrapping 8, filling the interstices thereof. The compound preferably used is such 60 that it will dry quite rapidly so that the conductor may be reeled or taken directly to the next step in the fabrication of the cable.

65 In order to distinguish the polarity of individual conductors which are later made up into a cable, suitable coloring matter may be

added to the compound and the cable may be made up of individual conductors thus differently colored and distinguished. The externally presented valleys between the individual conductors may be and preferably 70 are filled with a suitable cord 14 of jute or other appropriate material arranged to fill out the valleys so as to provide cable which as a whole is substantially round in cross-section. These cords are preferably treated 75 with the fire proofing compound used in treating the individual insulated conductors and may be of material so selected as to add to the tensile strength of the cable as a whole.

The individual conductors suitably assembled to form a substantially round cable are bound together by a sheath of suitable material characterized by a relatively high tensile strength and insulating value as well as being substantially impervious to moisture. 80 For this purpose, I have found to be satisfactory a rubberized fibrous material such as a strip of paper containing a rubber compound. This sheath is designed not only to securely bind the several conductors together but also to provide a protection against moisture or abrasion or the effects of any deleterious substances such as salts and alkalis used in winter weather to keep switches, frogs and the like from freezing.

95 In the particular structure shown the sheath consists of a laminated strip providing a strip of substantial width and of multiple thickness to insure strength and imperviousness. It is wound in overlapped relation, each 100 successive turn overlying substantially one-half of the width of the previous turn so as to provide a continuous sheath which is entirely moisture-proof. It is wound under considerable tension so that the overlying half 105 width will compact and usually wrinkle the inner half width of the preceding winding over which it is wound. The character of the material is such that there is a substantial adhesion between successive layers.

110 The rubberized strip shown consists of rubber impregnated laminated paper and in itself is more or less inflammable. For this reason it may be desirable to apply a coating of fire proofing or fire resisting material 115 thereto. Such a coating is indicated at 19. The same fire resisting and water proofing compound as used in treating the braid 10 and paper 8 may advantageously be used.

120 Surrounding this rubberized paper there is provided a cord casing, the cord being braided as indicated in Figure 1. As shown three parallel cords are arranged to form each strand 16 and the several strands are braided to form a substantially continuous casing 17 enclosing 125 the whole cable. This cord jacket is treated with a fire and water proofing compound as indicated at 18 compounded to afford great resistance to mechanical injury and substantial or complete imperviousness to water and 130

- other destructive liquids which are likely to come into contact with the cable under the conditions of use for which the cable is more particularly designed. The compound particularly selected for use in the preferred form of cable consists principally of lithopone and barytes with a relatively small proportion of linseed oil. This compound is preferably somewhat thick and of a character to harden to form a relatively hard and tough coating. It is applied to the jacket in a manner to thoroughly impregnate the same and to form on its exterior a coating of substantial thickness whereby it, with the cord jacket forms a relatively hard and tough casing which offers great resistance to abrasion as well as to damage by heat.
- The embodiment of the invention described provides a homogeneous compact structure which is relatively inexpensive to manufacture and yet its qualities are far superior to those of even more expensive materials now in common use.
- Although only one embodiment of the invention has been shown and described herein it will be understood that the invention may be variously modified and embodied within the scope of the subjoined claims.
- I claim:
1. As an article of manufacture an electrical cable comprising in combination, metallic electrical conductors, a surrounding sheath of rubber insulating compound for each of said conductors, a protective covering in strip form closely wound about each of said insulated conductors, a fabric jacket surrounding each of said protective coverings, a rubberized fibrous strip surrounding the several conductors and binding the same together, said strip being wound helically in overlapped relation, one-half of the width of each wrapping overlying one-half of the width of the preceding wrapping and being wrapped tightly to compress the overlapped portion, and an enclosing casing treated with fire and waterproof material consisting principally of lithopone and barytes.
2. An electrical cable as defined in claim 1 wherein the rubberized fibrous strip consists of a multi-ply paper, the separate plies of which are secured together by the rubber.
3. As an article of manufacture an electrical cable comprising in combination metallic electrical conductors, a surrounding sheath of rubber insulating compound for each of said conductors, a protective covering in strip form closely wound about each of said insulated conductors, a fabric jacket surrounding each of said protective coverings, said jacketed insulated conductors being arranged one centrally and the remaining in a circle thereabout to provide a substantially circular cable, a rubberized fibrous strip surrounding the several conductors and binding the same together, said strip being wound helically in overlapped relation, one-half of the width of each wrapping overlying one-half of the width of the preceding wrapping and being wrapped tightly to compress the overlapped portion, and an enclosing casing treated with fire and waterproof material consisting principally of lithopone and barytes substantially as described.
4. A cable which comprises the combination of an insulated conductor, an armor enclosing the conductor and made up of a non-metallic strip wound helically about the conductor and with the convolutions overlapping.
5. A cable which comprises an insulated conductor, a bedding about the conductor, an armor on the bedding made up of overlapping convolutions of non-metallic tape, and a protective covering over the armor.
6. A cable which comprises the combination of an insulated conductor and an armor enclosing the conductor and made up of a laminated non-metallic strip wound helically about the conductor with adjacent convolutions overlapping.
7. A cable which comprises the combination of a plurality of individually insulated conductors and an armor enclosing and binding the several conductors together, said armor being made up of a non-metallic strip wound helically about the assembled conductors with the convolutions overlapping.
- In testimony whereof, I have signed my name to this specification this 9th day of September, 1924.
- CHARLES WILLS ABBOTT.
